DESIGN FOR A PILLOW SLIP OR SIMILAR ARTICLE

Joseph L. Freund, New York, N. Y.

Application August 23, 1935, Serial No. 58,268

Term of patent 3½ years

To all whom it may concern:

Be it known that I, Joseph L. Freund, a citizen of the United States, residing at 27 West 96th Street, New York, New York, have invented a new, original, and ornamental Design for a Pillow Slip or Similar Article, of which the following is a specification; reference being had to the accompanying drawing forming a part thereof,

The figure is a plan view of a pillow slip showing my new design.

I claim:

The ornamental design for a pillow slip or similar article, as shown.

In testimony whereof I have signed this specification.

JOSEPH L. FREUND,
